US00D828924S

(12) **United States Design Patent** (10) **Patent No.:** **US D828,924 S**
(45) **Date of Patent:** **** Sep. 18, 2018**

(54) **MASSAGE TOOL**

- (71) Applicant: **Rocktape, Inc.**, Campbell, CA (US)
(72) Inventors: **Cullen Maxwell Maroney**, Campbell, CA (US); **Gregory van den Dries**, Los Gatos, CA (US); **Steven Capobianco**, Highlands Ranch, CO (US)
(73) Assignee: **Rocktape, Inc.**, Campbell, CA (US)

(**) Term: **15 Years**

(21) Appl. No.: **29/610,198**

(22) Filed: **Jul. 10, 2017**

(51) LOC (11) Cl. **28-03**
(52) U.S. Cl.
USPC **D24/200**; D24/215

CLAIM

The ornamental design for a massage tool, as shown and described.

DESCRIPTION

FIG. 1 is a perspective view of the massage tool in accordance with an embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the massage tool of FIG. 1 inserted into a first unclaimed sleeve; and,

FIG. 9 is a perspective view of the massage tool of FIG. 1 inserted into a second unclaimed sleeve.

The broken lines in FIG. 8-9 illustrate details of optional and/or environmental features that form no part of the claimed design.

1 Claim, 3 Drawing Sheets
